METHOD AND APPARATUS FOR
CONDITIONING AIR

Charles R. Downs, Old Greenwich, Conn., assignor, by mesne assignments, to The Calorider Corporation, Greenwich, Conn., a corporation of Connecticut

Application June 25, 1937, Serial No. 150,230

16 Claims. (Cl. 183—120)

This invention relates particularly to the conditioning of air or other gases by means of dehumidification by processes in which it is necessary to remove heat from and cool the air or gases and dehumidifying agents during the operation of the air or gas conditioning unit, but it may also be used for the removal of other vaporous constituents from air or other gases by suitable absorbents. The invention relates 10 both to the method and to the apparatus in which the method may be practiced.

In methods of conditioning gaseous fluids by means of dehumidification using moisture absorbing materials in either liquid or solid form, 15 heat is liberated and unless removed, the moisture absorbing materials rise in temperature. If this rise is not restrained further moisture removal from the gaseous fluid ultimately stops. When solid absorbing materials are used this 20 cooling is generally primarily effected by transfer of heat to the gaseous fluid being dehumidified. When liquid moisture absorbing materials are used they are generally removed from the conditioning zone, heat previously absorbed by 25 them is extracted therefrom and the cooled liquid returned to the conditioning zone to absorb further moisture and heat. Similar methods have also been employed for removing other vaporous constituents from air or other gases.

30 In the copending applications Ser. Nos. 57,148 and 98,646 of Charles R. Downs and Joseph W. Spiselman methods and apparatus are shown and described in which latent heat of condensation of moisture is converted to sensible heat 35 and together with sensible heat in the air or gaseous fluid entering the apparatus is absorbed by a liquid moisture absorbing material and extracted at the moment of absorption by a cooling fluid such as water which is in indirect heat 40 transferring relationship with the liquid moisture absorbing material. The cooling water carries the heat away from the process or apparatus.

Where city or well water has been used as the cooling fluid, the cost of the water required to 45 carry away the heat has been an important factor in the cost of carrying out the process and there are many instances where the water obtained from natural sources is at too high a temperature to effect adequate cooling especially 50 where the air must be cooled to temperatures considerably below that of the space to which it is to be transferred.

To reduce this cost and to conserve water supplies proposals and attempts have been made 55 to use an evaporative water cooling tower to

which the water discharged by the apparatus is conducted and passed in contact with atmospheric air and the water so cooled is returned to the apparatus and then used to extract heat from a moisture absorbent material after which 5 the water is recycled through the cooling tower for recooling by evaporation. For the purpose of obtaining cooler water than can be produced by its evaporation in contact with atmospheric air, the use of predried air has been proposed. 10

Heretofore known methods of using cooling towers for this purpose are objectionable for the reason that the cost of installation is high because the point of location of the cooling tower is separated from the air conditioning apparatus 15 requiring extensive piping and pumping equipment for taking the water which has absorbed heat to the tower and returning the cooled water to the air conditioner for further heat absorption. The cost is further increased by 20 the necessity for lagging the cooling water recirculating equipment from the cooling tower to the air conditioning apparatus and return, the cooled water from the cooling tower is heated to some extent by conduction through the equipment walls and also somewhat by the mechanical 25 energy required to force the water through the resistance of the piping circuit. When the atmospheric dew point is high the cooling water additionally gains some heat due to condensation of moisture externally on the pipe walls or other parts unless this is prevented by the use of special and expensive moistureproof insulation. Heat is also introduced from similar external sources through the walls and supports 30 of the cooling tower and the air conditioning apparatus. When the cooling liquid is cooled by any other outside cooling means the same 35 type of disadvantages are met.

It is an object of my invention to reduce external heat gains into a gas conditioning system to a minimum by providing an apparatus and method in which the gas is purified of vapors or other gases to an unsaturated condition and cooled in a gas conditioning chamber combined 45 with an evaporative water cooling chamber where cool water is produced for cooling the former in such manner that the apparatus may be installed or used as a single unitary structure. The evaporative water cooling chamber may be 50 one in which water is cooled by vaporization into a stream of either ordinary atmospheric air or air which has been predried or in which water is evaporated under the application of a partial vacuum. The vapors or other gases re- 55

moved from the gas may be absorbed or adsorbed by a suitable substance or form a chemical compound therewith.

Another object of my invention is to provide an apparatus and method of the type described in which a water evaporative cooling jacket surrounds and encloses an absorption air conditioning chamber for conditioning air to a moisture unsaturated state in such a manner as not only to insulate the sides of the air conditioning chamber from the surrounding atmosphere but also to simultaneously cool the sides of the air conditioning chamber.

Another object of my invention is to provide a water evaporative cooling chamber and an absorption air dehumidifying chamber in a unitary structure which can be installed in a restricted space without the necessity of extensive alterations to the building or of extended lines of piping and ducts for connecting a separated cooling tower to a dehumidifying unit since all the heat resulting from the production of dried and cooled air is removed directly from the structure itself in the form of water vapor.

Another object of my invention is to provide an air conditioning apparatus in which air is dehumidified to a moisture unsaturated state by a hygroscopic liquid flowing concurrently therewith through a dehumidifying chamber combined with an evaporative cooling jacket for the dehumidifying chamber to form a unitary structure of high efficiency and in which surfaces common to both effect desirable heat transfer in such a manner that the cooling effect of the evaporative cooling jacket is concurrent to the flow of air and hygroscopic liquid.

A further object of my invention is to provide an evaporative cooling chamber and an air dehumidifying chamber as one structural unit in such manner that two or more of these units may be conveniently connected together so that the moisture unsaturated air from the first unit may be conveyed to the evaporative cooling chamber of the second unit to remove heat from the second unit to thereby produce a lower temperature in the dehumidifying chamber of the second unit and thereby permit conditioned air of lower moisture content and lower temperature to be delivered from the second or any later unit in the series than would be possible by the use of only a single unit.

A further object of the invention is to produce moisture unsaturated air by contact with a cooled hygroscopic liquid in an air conditioning chamber, divide the air so produced into two streams one of which is passed through an evaporative water cooling chamber in which the cooling effect so produced is concurrent to the flow of hygroscopic liquid in a dehumidifying chamber used to further dry and cool the second stream of air.

A still further object of the invention is to provide a system whereby air may be cooled during absorptive dehumidification solely by evaporative cooling within a unitary structure in such a way that air so conditioned may be discharged therefrom at a temperature or moisture content each suitable for comfort conditioning even under extreme atmospheric conditions and at the same time to obtain these results with a minimum of equipment, occupying a minimum of space at a low operating cost.

Various other objects and advantages of my invention will appear as this description proceeds.

In one form of dehumidifier-cooler according

to the present invention the cooling water passing through the dehumidifier portion is discharged directly to its evaporative cooling jacket where it is sprayed down countercurrent to a stream of air rising through this jacket. As the water cools as it proceeds downward, its cooling effect transmitted through the common wall of the dehumidifier and jacket is concurrent to the flow of dehumidifying solution inside. Just as with the internal cooling water in the heat exchange unit of the concurrent flow dehumidifier, the temperature decreases from top to bottom despite the fact that it is flowing in the opposite direction.

The use of the annular space around the dehumidifier to form the evaporative cooling jacket allows a large available cross section which enables the height of the apparatus to be kept down and at the same time the outside dimensions of the entire equipment are at a minimum.

This new form of apparatus has made it possible to carry out very efficient air conditioning operations, including both dehumidification and cooling of the air and by including certain additional provisions both functions can be maintained regardless of outside atmospheric conditions. Independence of outside atmospheric conditions may be accomplished by supplying the evaporative cooling jacket with air, the wet bulb temperature of which is satisfactory or has been adjusted to a desired point, thereby enabling the jacket to remove heat from the unit in the form of moisture vapor and at a lower temperature than could be accomplished with outside air under adverse weather conditions. For such purposes, for example, two dehumidifier-cooler units each comprising an extended surface heat exchange dehumidifier and its evaporative cooling jacket may be employed. In one of these units atmospheric air is dehumidified and cooled to the extent possible by using a circuit of cooling water whose temperature is continuously adjusted by contacting with atmospheric air in the evaporative-cooling jacket of the first dehumidifier-cooler. This dehumidified and cooled air is then used in the evaporative cooling jacket of the second dehumidifier-cooler, which cools and dehumidifies the air designed to be used in the conditioned space.

By this system the hygroscopic solutions or other hygroscopic material convert the latent heat load of the air to be treated into sensible heat and this plus the sensible heat of the entering air is removed in the form of water vapor. The heat in the first dehumidifier-cooler may be removed at a relatively high temperature level where evaporative cooling with atmospheric air in the evaporative jacket portion will suffice and the so treated air will develop a materially lower temperature level in the evaporative cooling jacket of the second dehumidifier-cooler so that the air treated therein can be completely adjusted to the conditioning requirements. When a second dehumidifier-cooler is used in series, the humidity and the temperature of the air delivered to the conditioned space can be independently controlled, the former by the conditions of the dehumidification operation and the latter by the character of the air supplied to the evaporative cooling jacket. Under some conditions atmospheric air or air taken from the conditioned space or a mixture of outside and inside air may be used in the evaporative cooling jackets of either one or more of the conditioned units.

When the air to an evaporative cooling jacket

of a dehumidifier-cooler is first treated by a dehumidifier, the heat may be removed from this dehumidifier by any suitable means, such as city water, well water or recycled water from an ordinary atmospheric cooling tower or by water evaporating under a vacuum in an evaporative cooling jacket surrounding the dehumidifier.

In the system of air conditioning herein provided only a relatively small portion of the energy input into the system is in the form of electric energy to transport air and liquids. The bulk of the energy input, that is the requirements to remove the latent and sensible heats of the air conditioned, is supplied to the system in the form of heat to the concentrator and this heat may be applied in any form so that the cheapest available fuel source will be adequate. Moreover the system conserves and utilizes this energy in a highly efficient manner so that operating costs are below those of heretofore known systems. Moreover advantage is taken of any moisture unsaturation of atmospheric air or other air which is available and this potential energy is substantially completely utilized in the system.

The foregoing discussion has considered only two units in series, but the scope of the invention includes a series of any desired number of units in which the air produced in one unit is used in the evaporative cooling jacket of the unit next in the series thereby producing colder and colder water through the series and consequently colder and colder air which at the same time is lower and lower in absolute humidity from one to the other of the units in the series to a practical limit.

While the dehumidifying-cooler unit described and illustrated herein is of the concurrent flow solution type as described in copending applications Ser. Nos. 57,148 and 98,646, it will be understood that other types of dehumidification units may be incorporated into a unitary structure with an evaporative cooling jacket as described herein to form a dehumidifier-cooler.

In the form of embodiment of the invention illustrated in the accompanying drawings:

Fig. 1 is a sectional view of a preferred form of embodiment in which the evaporative cooling jacket surrounds a dehumidifying unit of the type described in copending application Ser. No. 50 98,646.

Fig. 6 is a sectional view of a modified form of apparatus in which a soft water or other cooling liquid circuit is used for the heat exchange unit of the dehumidifier;

Fig. 7 is a sectional view showing a dehumidifier-cooler portion comprising an evaporative cooling jacket and a liquid phase dehumidifier which also supplies cooled water to the solid drying zone of the type shown and described in copending application Ser. No. 57,148; and

Fig. 8 is a schematic view showing the air from one dehumidifier-cooler unit divided and part used for cooling the water of a second unit while the remainder is passed through the dehumidification portion of the second unit to be further cooled and dehumidified.

In Figures 1, 2 and 3 the numeral 1 represents a dehumidifier-cooler which comprises a concurrent flow extended surface heat exchange dehumidifier 2, and an evaporative cooling jacket 3. The dehumidifier portion 2 contains an air inlet duct 4, a series of pipes 5 and hygroscopic liquid spray nozzles 6, an extended surface heat exchange unit 7 containing conduits 8 and fins 9, as described in said copending application Ser. No. 98,646, a chamber 10 containing an air deflecting baffle 11 which may be perforated for drainage of liquid as shown by the arrows in Fig. 1 and a sump 12, an outlet section 13 containing spray eliminators 14 and 15 from which curtains 14a and 15a hang downwardly and whose bottom edges are sealed by the liquid in sump 12 to prevent air from bypassing the spray eliminators 14 and 15 and an outlet opening 16 through which the air which has been conditioned is discharged for use. The evaporative cooling jacket 3 surrounds all four sides of the dehumidifier portion 2 and is separated therefrom by a heat conducting wall 17. Figure 1 shows a plate 14b which is provided with small liquid drainage holes to permit the small amount of liquid separated from the air by the eliminator 15 to drain into sump 12.

Jacket 3 constitutes an annular space whose outside walls are shown as 18, which are preferably lagged, its ceiling as 19 and its floor as 20. Within the jacket 3 a pipe 21 encircles the portion 2 and is provided with nozzles 22 for creating sprays of water. Below spray nozzles 22 the jacket 3 may be provided with a filling material 24, which may be composed of slats, hurdles, Rasching rings, Berl saddles or other baffling means for spreading out thin layers of water over very extended surfaces. When this filler 24 is of a loose type it may be supported upon screens 25. Below the filling material 24 and above the floor 20, I prefer to provide an open annular space 26 surrounding portion 2 in order to distribute air to all parts of the evaporative jacket 3 from air inlet 27. Air is discharged to waste through outlet 28 after it has passed through the evaporative jacket 3 and any water spray carried therein may be extracted by means of a spray eliminator 29. Spray eliminators 15 and 29 are primarily designed to eliminate fine spray droplets and I have found glass wool sheets suitable for the purpose. The apparatus is designed to provide simple cleaning of such fine eliminators in that they may be removed easily by sliding them out of the openings 15b and 29a after which they may be replaced and the openings sealed in any suitable manner.

For circulating cooling water and hygroscopic solution a double ended shaft motor 30 connected to the hygroscopic solution pump 31 and a water pump 32 may be provided. The section of the water pump 32 has a short inlet pipe 33 leading from the space above the floor 20 and it discharges through a short pipe 34 to the inlet or header 35 for the tubes 8 of an extended surface heat exchange unit 7 in the dehumidifying zone 65 or chamber 2. Wherever pipes 33 and 34 extend beyond the walls of the unit, I prefer to thoroughly insulate them. The outlet header 36 of the heat exchange unit 7 is connected by pipe 37 to pipe 21 which is provided with spray nozzles 23, said pipe encircling the upper part of the evaporative cooling jacket zone 3. As water is evaporated in jacket 3 and is carried off with the discharged air through 28, make-up water is fed through pipe 40 and valve 41 which is under the 75

control of float 42 to maintain a layer of water upon the floor 20.

The pump 31 has its suction connected to sump 12 for the hygroscopic liquid by means of pipe 43 and its discharge connected to pipe 44 which is branched to connect to pipes 45 and 46. These pipes are valved at 45a and 46a respectively to proportion the quantity of hygroscopic liquid discharged through each and are preferably short and insulated. Branch 45 leads to header 47 and pipes 5 provided with nozzles 6. As the hygroscopic liquid removes water from the air passing through the dehumidifier 2, it becomes more dilute and this water must be removed, hence a portion of the hygroscopic liquid is continuously discharged through branch 46 to a reconcentrator as shown for example in copending applications Ser. No. 98,646 and Ser. No. 144,630 wherein its construction and operation are described in detail or to any other suitable type of concentrator. Concentrated hygroscopic liquid is returned from the reconcentrator to sump 12 by pipe 56.

The operation of the dehumidifier-cooler unit is as follows. Air enters the dehumidifier zone 2 of the unit 1 through the air inlet 4 and contacts with the sprays 6 of hygroscopic liquid such as water solutions of calcium chloride, lithium chloride or the like. The air in a plurality of thin streams passes through narrow channels formed by arranging the fins 9 in closely spaced substantially parallel order and the hygroscopic liquid spread in thin films upon the heat conducting surfaces or fins 9 flows concurrently with the air through the extended surface heat exchange unit 7. The hygroscopic liquid while absorbing moisture from the air absorbs the latent heat of condensation of the condensed moisture and sensible heat from the air and this heat is transferred at the instant and position of formation or absorption to the water flowing inside the tubes 8 of the heat exchange unit 7. The air and hygroscopic liquid leave the heat exchange unit 7 in substantial equilibrium with each other and at the lowest temperature reached in the dehumidifying zone 10 and separate from each other in chamber 10, the hygroscopic liquid flowing down the perforated baffle 11 to the sump 12 for recirculation through the unit and the air passing through the eliminators 14 and 15 to the outlet 16 from which it is discharged to the space to be conditioned or to another conditioning unit in the series, as described later.

In the application Ser. No. 98,646, the cooling fluid used for removing the heat from the extended surface heat exchange unit 7 was obtained from any suitable source. In the present construction, the cooling fluid is water and its temperature is continuously adjusted by evaporating water within the apparatus itself.

Air from any suitable source is caused to enter the inlet 27 by means of a blower 28a and pass through the space 26 surrounding the wall 17 under the screen 25. It then passes upwardly through the evaporative cooling jacket 3 which may be an unfilled space but is preferably filled with suitable baffles which are wetted by a downward flow of water originating from the spray nozzles, 23. The counterflowing air evaporates a portion of the downflowing water and air of high relative humidity carrying away the heat discharges to waste through 28 for example to the outdoor atmosphere. Care should be taken to prevent the discharge of this air closely adjacent to the air inlet 4 for the dehumidification unit 2, 70 should this draw air from outdoors, so that the

heavily moisture-laden air from 28 will not short circuit into air inlet 4 or into air inlet 27, should this be designed to receive its air from outdoors. This requirement can be satisfied by the use of properly placed ducts. I prefer to use a blower 5 to draw air from the evaporative jacket rather than force it into the same as by this means the air entering the jacket is not heated by compression.

The water, in excess of that evaporated, having been cooled by the evaporating water drains on to the floor 20 and is forced by pump 32 directly through the heat exchange unit 7 of the dehumidifier 2 back to the nozzles 23. Entrained water is separated from the air before it discharges through outlet 28 by the spray eliminator 29. Any unavoidable loss of water due for example to poor elimination plus that loss by evaporation is made up by means of the float valve 42 and the water inlet valve 41. The water resting upon the floor 20 is the coldest portion of the water in the circuit while that discharged from the nozzles 23 after having passed through the heat exchanger 7 is the warmest portion at any moment. As the water flows down through 18 the evaporative cooling jacket 3 its temperature is decreased and the wall 17 is progressively cooled toward the bottom of the heat exchange section 7. The temperature differentials of the water in the various parts of the circuit may not be great if the rate of circulation is rapid. I thus provide progressive cooling of the descending hygroscopic liquid and air in the chamber 2 both internally and externally. In addition to this I provide by means of jacket 3, a method of insulating the dehumidifier section 7 from outside heat.

To prevent heat from being transferred from the surrounding atmosphere into the evaporative cooler jacket 3, I prefer to cover its exterior with suitable heat and moisture insulation and a considerable saving in cost of installation is permitted in that the lagging of the wall 17 is rendered unnecessary. The compact nature of my dehumidifier-cooler permits the shortest possible pumping lines, thereby reducing resistance to liquid flow, 45 reducing cost of piping and of pipe lagging to prevent heat absorption by the flowing liquids. Operating costs are reduced and heat losses are at a minimum and the compactness of the unit requires a minimum of floor space.

Ample evaporative cooling surfaces may be provided with the screens 25 located as illustrated without increasing the height of the jacket 3 or increasing its horizontal dimensions beyond the proportions shown. For example the horizontal 55 dimensions of the dehumidification chamber 2 may be three feet square giving a face area of nine square feet for the extended surface heat exchange 7 and a one foot wide annular evaporative cooling jacket 3 will have a plane area of sixteen 60 square feet. Hence I may use a shallow depth of filler material 24. With the dimensions given above the floor space occupied, excepting the outlet section 13, is only five feet square and the unit will dehumidify and cool 5,000 to 6,000 cubic 65 feet of air drawn from outdoors per minute in temperate climates.

This type of evaporative jacket for cooling the water passed through tubes 8 of heat exchange unit 1, is also of advantage when for example the 70 evaporative jacket 3 is to be operated under vacuum. In such a case, the inlet 27 is sealed or not provided, and a means of evacuating the jacket 3 is connected to outlet 28. As shown in Fig. 4, the inlet 27 may be closed by a damper 75

or valve 27a to prevent intake of air to the jacket. The blower 28a will thus suck air from the jacket and create a partial vacuum, facilitating the evaporation of water in the jacket. Any other suitable means for closing the inlet and for creating a partial vacuum in the jacket may be employed.

Independent control of the temperature and humidity within a space conditioned for comfort can be provided by the dehumidifier-cooler as described herein. To attain this objective, a thermostat in the conditioned space C may be used to control the temperature thereof by varying the temperature of the produced conditioned air by varying the degree of vacuum in the evaporative cooling chamber or by varying the quantity of moisture evaporated to the air passed therethrough to be humidified and a humidostat similarly placed may be used to control the moisture content of the space by varying the moisture absorbing character of the hygroscopic liquid by varying its concentration. One method of doing this is illustrated diagrammatically in Fig. 4. The thermostat D in the conditioned space C controls the speed of the motor of the blower 28b to vary the extent of partial vacuum in the jacket, and a humidostat E in the conditioned space controls the regulating valve 46a so as to control the flow of hygroscopic liquid to the concentrator 55. Spaces containing other gases may be controlled similarly.

The air passed into inlet 4 of the dehumidification unit 2 may be all outdoor air or air recirculated from the conditioned space or a mixture of the two depending upon the amount of ventilation required in the conditioned space or it may be air which has been reduced in another suitable apparatus below the temperature and/or moisture content of outdoor air. The air discharged from outlet 13 may all be sent to the conditioned space or it may all be discharged to the evaporative cooling jacket of a second air conditioning unit for the purpose of producing a lower temperature therein than can be attained when using untreated air or it may be passed through an evaporative cooling tower of any suitable type for producing cold water for various uses, or it may be divided and part used for evaporative water cooling and part further dehumidified as described in connection with Fig. 8. The air entering inlet 27 may be outdoor air or air whose temperature and/or moisture content has been reduced such as that obtainable from outlet 13 of another unit or it may be waste air discharged from the conditioned space or mixtures of the above air qualities.

Fig. 5 illustrates in further detail how the evaporative cooling jacket 3 surrounds and insulates the dehumidification section 2.

Fig. 4, for example, shows two conditioning units A and B each having a dehumidification chamber 2 receiving air from a duct 4 and discharging conditioned air from the outlet 13 and each surrounded by an evaporative cooling jacket 3 and being constructed and operated in accordance with Figs. 1, 2 and 3.

The unit A may receive outdoor air into the duct 4 for dehumidification and cooling in the section 2, and may receive outdoor air into the inlet 27 to pass through the jacket 3 to cool the water used in the unit A. The air inlet 27 of the unit B, however, is connected with the outlet 13 of the unit A to receive dehumidified air from the unit A and use this drier air to evaporate and cool the water in the cooling jacket 3 of the unit B

so as to provide cooler water for use in the dehumidification section 2 of the unit B than if only atmospheric air were used to cool the water in unit B.

In this manner a lower temperature level is provided in the unit B than in the unit A and air of lower moisture content and temperature is discharged from the outlet 13 of the unit B than can be provided in the unit A.

By using two or more units connected as illustrated in Fig. 4, air of any desired degree of temperature and moisture content within the limits of human comfort may be provided for discharge from the last unit of the series, into the conditioned space which is illustrated at C in Fig. 4.

Also in this arrangement, it is possible to recirculate the air from the conditioned space through one of the conditioning units, and thereby avoid the expense of having to condition all outside air. As illustrated, air from the conditioned space C may be drawn out through the duct 50 and conveyed into the inlet duct 4 of one of the conditioning units such as B and by means of suitable dampers 51 and 52 the amount of inside air recirculated may be proportioned to the amount of outside air taken in through the outside air duct 53 to provide any desired proportion of fresh to recirculated air.

The blowers 28a and 28b might be in the inlet ducts 27 but I prefer the placement of them in the positions as shown. For example, in the case of blower 28a the heat generated by forcing the air through the evaporative jacket of unit A is discharged to the atmosphere and is not a burden upon this cooling jacket. The blower 28b draws air into the dehumidifying chamber 2 of unit A and thence through jacket 3 of unit B and the heated air is discharged to the atmosphere to waste. The blower 4a draws air through 53 or 50 or a mixture of both, forces it through chamber 2 of unit B and through the distributing duct to the conditioned space. Any heat formed by the blower 4a is removed in the chamber 2 and the air is not reheated as it would be were the blower 4a placed in the outlet 13 of unit B.

In order to maintain the hygroscopic solution circulating through the dehumidifying sections 2 in a condition of proper concentration, a specified portion thereof, for example, one-fifth ($\frac{1}{5}$) to one-sixth ($\frac{1}{6}$) is diverted through the pipes 46 to the reconcentrator 55, which may serve one or more conditioning units of the type illustrated by A and B, where heat is applied to the hygroscopic solution to drive off the water absorbed from the air and the reconcentrated hygroscopic solution returned through the pipes 56 to the sump 12 for circulation through the dehumidification section 2. The operation and control for the reconcentrator is described in greater detail in the copending applications Ser. No. 98,646 and 144,630.

In the embodiment of the invention illustrated in Fig. 6, the dehumidification section is indicated at 2 and the evaporative cooling jacket at 3. The heat exchanger 7 and its pumping circuit receives soft water or other suitable liquid from an expansion tank 60 through the pipe 61. This liquid is circulated through the pipes 62, pump 63 and coil 64 immersed in the evaporative water on the bottom 20 of the jacket 3 and pipe 65 to the pipes 8 in the heat exchanger 7 and back through the pipe 62. In this way the liquid which is not evaporatively cooled may be continuously circulated through the heat exchanger 7.

and is cooled in its flow through the coil 64 immersed in the cooled water in the bottom of the evaporative cooling jacket 3, to thereby prevent the formation of scale in the conduits in the heat 5 exchanger 7. The coils 64 as shown extend three-fourths of the way around the chamber 2 to provide ample heat transfer surfaces. Ordinary or even hard water may be circulated through the cooling jacket 3 by the pump 32 as described in 10 connection with Fig. 1 and the hygroscopic solution may be circulated over the surfaces of the heat exchanger 7 by the pump 31. But for the separate liquid circuit, the operation of the apparatus illustrated in Fig. 6 is essentially similar 15 to that illustrated in Figs. 1 to 3.

The pump 31 withdraws the hygroscopic liquid from the sump 12 through the pipe 43 and discharges it through pipes 44 and 45 to the pipes 20 5 and spray nozzles 6 from which it flows concurrently with the air through the heat exchanger 7 to dehumidify the air. The pump 32 withdraws cooled water from the bottom 20 of the jacket 3 through the pipe 33 and pumps it, 25 through the pipe 34a, to the header 21 where it flows around the top of the jacket 3 and is sprayed by the nozzles 23 into the air stream passing upward through the jacket 3, where heat is removed from the apparatus by evaporation of part of the water and the remainder is returned to the pool 30 in the bottom 20 of the jacket 3. Here it withdraws heat from the liquid flowing through the immersed coils 64 on its way to the heat exchanger 7.

This type of evaporative jacket containing 35 cooling coils for heat exchange between the evaporative water and the cooling liquid passed through the conduits 8 of heat exchange unit 7 is also of advantage when for example, the evaporative jacket 3 of a unit is to be operated under 40 a vacuum. In such a case the duct 27 is closed or not provided and a means of evacuating the jacket is connected to duct 28.

In the embodiment of my invention illustrated in Fig. 7, the evaporative cooling jacket 3c is shown applied to the liquid phase dehumidifier 2c of a combined liquid and solid phase dehumidifier 70 of the type illustrated and described in 45 pending application Ser. No. 57,148. It will be understood, however, that the evaporative cooling jacket 3c may be made to surround the entire dehumidifier 70 if desired.

In this embodiment the air to be dehumidified enters the duct 4c and contacts with the sprays 6c of hygroscopic liquid and flows concurrently 55 with the hygroscopic liquid through the passages of the heat exchange unit 7c and past the spray eliminator 14c into the solid phase dehumidification section of the dehumidifier 70.

In the solid phase section of the dehumidifier 60 the air passes through the beds 71, 72 and 73 of solid dehumidification material, such as calcium chloride, and is discharged through the ducts 74 and 75 to the space to be conditioned. Between the beds 71 and 72 and the beds 72 and 73 the 65 air passes through heat exchange units 76 and 77 where part of the heat of dehumidification generated in the beds of solid material is removed.

As the solid dehumidification material in the beds 71, 72 and 73 is liquefied by the moisture 70 removed from the air passing therethrough, the liquefied material and small residual particles of solid material drop through the screens 78 into the pool or sump 12c of liquid hygroscopic material in the unit 70 from which it is picked up by 75 the suction line 79 of the pump 80 and conveyed

through the pipe 81 to the spray nozzles 6c. If too much liquid hygroscopic material accumulates in the sump 12c the float 82 energizes an electrical circuit 83a and 83b to the electrically controlled valve 84 in the pipe 81b to open this valve and permit excess hygroscopic liquid to be discharged through the pipe 81b. As the solid material is dissolved in the beds 71, 72 and 73, additional solid material feeds down from the bins 71a, 72a and 73a.

The motor 85 drives a fan in the conduit 75 and also by means of a belt connection 85a drives the pump 80, all as more completely described in said copending application Ser. No. 57,148. The fan may be so connected to the apparatus to blow air into the duct 4c rather than draw it through the apparatus as shown.

The heat exchange unit 7c and also the heat exchangers 77 and 76 are cooled by water from the evaporative cooling jacket 3c by means of a 20 pump 86 which receives water through the pipe 87 from the bottom 20c of the evaporative cooling jacket 3c and pumps it through the pipe 88 to the heat exchanger 77 from which it flows through the pipe 89 into the heat exchanger 76 25 and thence through the pipe 90 into the bottom of the heat exchanger 7c. From the top of the heat exchanger 7c the water flows through the pipe 91 to the manifold 21c and spray nozzles 23c where it is sprayed down over the packing material 24c in the jacket 3c. At the same time air from any suitable source is being drawn through the inlet 27d of the evaporating cooling jacket 3c and discharged through the outlet 28c preferably to the outdoor atmosphere by the fan 28d to cool 35 the water which is discharged from the nozzles 23c in the manner described in connection with Figs. 1 to 5. A float valve 41 controlled by a float 42 admits water from the pipe 40 to the bottom 20c of the cooling jacket to maintain the water 40 supply.

A further modified arrangement is shown in Fig. 8 in which the conditioned air from the outlet 13 of the unit A is divided between the ducts 27b and 56 and a portion passed through the 45 evaporative cooling jacket of a second unit B' and another portion through the dehumidifier section 2 of the unit B' to be further cooled and dehumidified. Suitable dampers 21c and 56a are provided for proportioning the air flow through 50 the evaporative cooling jacket and the dehumidifier section of the unit B' and the latter may be smaller than the unit A as it does not have as much air to cool and dehumidify and the air has already been partially treated. Fans 28a in the 55 outlets 28 for the evaporative cooling jackets provide air flow through these jackets, and a fan 57 in the duct 56 provides flow through this duct.

While I have described preferred forms of embodiment of my invention, it will be understood 60 that these particular forms of embodiment are for illustration only and that various modifications and changes may be made in these embodiments, all within the spirit of my invention or the scope of the claims.

I claim:

1. The process of cooling a gaseous fluid and dehumidifying it to an unsaturated state, which includes flowing the fluid through a dehumidifying zone containing a dehumidifying agent, cooling said fluid to progressively lower temperatures during said flow by transferring heat of moisture absorption to a cooling liquid within said zone but out of contact with said fluid, cooling said liquid in an evaporating zone in heat conducting rela- 75

tionship to said absorbing zone, by removing heat from said evaporating zone to progressively lower temperatures in step with those in the absorbing zone, and separating the gaseous fluid from the dehumidifying agent at the lowest temperature reached.

2. The process of cooling and dehumidifying a gaseous fluid to a moisture unsaturated state, which includes flowing a cooling liquid upwardly through a conduit in a moisture absorbing zone countercurrent to the flow of the gaseous fluid and to progressively higher temperatures, and thence downwardly through an evaporating zone separated from said absorbing zone by a heat conducting wall and to progressively lower temperatures, and delivering the gaseous fluid from the absorbing zone where said zone is cooled to its lowest temperature by the cooling liquid in both said conduit and said evaporating zone.

3. The method of dehumidifying air or other gases to a moisture unsaturated state, which comprises flowing air in directed paths through two zones separated by a heat conducting wall, passing a hygroscopic solution through one of said zones and concurrent with the air flowing therethrough to absorb moisture from said air and generate heat, circulating water out of contact with but in heat transfer relationship to the hygroscopic solution and countercurrent to the flow thereof to progressively cool the solution and warm the water, delivering said warm water into the upper part of the other zone to flow countercurrent to and in contact with the air in said last mentioned zone to partially evaporate the water and absorb heat by said air, thereby cooling the remaining water and said heat conducting wall, and circulating said remaining water for removing further heat from said solution.

4. The process of dehumidifying a gaseous fluid to a moisture unsaturated state by means of a hygroscopic material, which comprises passing the gaseous fluid in contact with said material in a dehumidifying zone, circulating water through cooling elements within said zone and in heat transfer relationship to said gaseous fluid and said hygroscopic material, evaporating a portion of the water delivered from said elements closely adjacent to the outer surface of a heat conducting boundary wall of said zone to abstract heat from said zone, cool the water and prevent absorption of heat from outside sources to said zone, and returning the unevaporated portion of the water to said cooling elements.

5. The process of dehumidifying a gaseous fluid to a moisture unsaturated state by means of a hygroscopic solution, which includes distributing hygroscopic solution throughout a current of said gaseous fluid to form an intimate mixture, preserving intimate contact of the solution and gaseous fluid of said mixture in divided form by flowing them as thin streams in the same general direction, progressively cooling and removing the heat of moisture absorption from said flowing mixture by circulating a cooling liquid between said streams, and out of contact with but in direct heat conducting relationship to and countercurrent to the said streams, evaporating liquid in contact with the outside of a heat conducting boundary wall in heat conducting relationship to said flowing mixture of gaseous fluid and solution to progressively cool and additionally abstract heat therefrom and prevent absorption of heat to said mixture from outside sources, and returning the unevaporated portion of said

liquid adjacent to said boundary wall for further evaporation.

6. The process of dehumidifying a gaseous fluid to a moisture unsaturated state by means of a hygroscopic liquid, which includes distributing 5 hygroscopic liquid throughout a current of said gaseous fluid to form an intimate mixture, preserving intimate contact of the hygroscopic liquid and gaseous fluid of said mixture in divided form by flowing them as thin streams in the same 10 general direction, progressively cooling and removing the heat of moisture absorption from said flowing mixture by circulating water between said streams, and out of contact with but in direct heat conducting relationship to and countercurrent to the said streams, evaporating some of the water adjacent to but outside of a heat 15 conducting boundary wall in heat conducting relationship to said flowing mixture of gaseous fluid and hygroscopic liquid to progressively cool and 20 additionally abstract heat therefrom and prevent absorption of heat to said mixture from outside sources and cool the water, and delivering the unevaporated portion of the water for recirculation 25 between said streams.

7. The method of removing a vaporous constituent from a gas by a suitable liquid absorbent, which comprises dividing the gas into a plurality of streams in an absorbing zone, flowing absorbent liquid in concurrent contact as thin films with 30 said gas streams, flowing water in direct contact with a directed countercurrent stream of moisture absorbing gas through a humidifying zone in direct heat conducting relationship with said absorbing zone to cool the water, removing heat 35 through said films of absorbent liquid to a countercurrent of said cooled water out of contact with but in heat exchange relationship to said films, and separating the said vaporous constituent 40 from the absorbing liquid.

8. The process for dehumidifying gaseous fluid such as air by the use of hygroscopic material, which includes passing the gaseous fluid in contact with the hygroscopic material in a dehumidifying and cooling zone, passing a portion of the 45 dehumidified gaseous fluid in contact with hygroscopic material in a second dehumidifying zone, passing the remainder of said gaseous fluid through a humidifying zone separated from said second dehumidifying zone by a heat transfer 50 wall, evaporating water in said humidifying zone to cool the water, cool said second dehumidifying zone and prevent absorption of heat to said heat transfer wall from outside sources, and circulating a cooling fluid through said second dehumidifying zone out of contact with but in heat transfer relationship to the gaseous fluid in said 55 second dehumidifying zone.

9. The method of independently controlling both the temperature and humidity of a gas in 60 an enclosed space by means of cooled and dehumidified gas discharged thereto which comprises simultaneous division of a current of gas into a plurality of narrow streams, association of flowing hygroscopic liquid in concurrent contact as thin films with said gas streams, removal of heat through said films of hygroscopic liquid to a current of cooling liquid, flowing in indirect heat exchange relation with said films in a dehumidifying zone, removing heat from said cooling liquid in a cooling zone as water vapor, said cooling zone being in heat exchange relation with said dehumidifying zone, separating the dried and cooled gas from hygroscopic liquid, discharging said gas to said enclosed space, discharging a 65 70 75

- part at least of said hygroscopic liquid to a concentrating zone, returning concentrated hygroscopic liquid to said dehumidifying zone to form further films and regulating the temperature of the enclosed space by varying the temperature level of the water vapor in the cooling zone and regulating the humidity of the enclosed space by varying the concentration of the hygroscopic liquid used to form said films.
10. In an air conditioning apparatus of the type described, a dehumidifying section having a passage through which the air to be conditioned may be passed in contact with dehumidifying materials, cooling conduits through which water may be passed in heat conducting relation to but out of contact with said dehumidifying materials to remove heat therefrom, an evaporative water cooling section separated from said dehumidifying section by a heat conducting wall, means for delivering water for evaporation in said cooling section, and means to deliver cooled water to said cooling conduits.
11. In an air conditioning apparatus of the type described, a dehumidifying section having a passage through which the air to be conditioned may be passed in contact with dehumidifying materials, cooling conduits through which water may be passed in heat conducting relation to said dehumidifying materials to remove heat therefrom, a water cooling section surrounding said dehumidifying section and in direct heat conducting relation therewith, means to spray said water, after passage through the cooling conduits in said dehumidifying section, into said water cooling section, means to pass other air in counterdirection through said water in the water cooling section to cool said water, means to return the cooled water to said cooling conduits, and means to introduce water to make up for that lost by evaporation.
12. In an air conditioning apparatus of the type described, a dehumidifying section, having passages through which the air to be conditioned may be passed in a plurality of fine streams in contact with flowing films of hygroscopic solution, cooling conduits through which water may be passed in indirect heat exchange relation to said films of hygroscopic solution to remove heat therefrom and a water cooling section adjacent said dehumidifying section and separated therefrom by a heat conducting partition, means to spray said water after passage through the cooling conduits in said dehumidifying section into said water cooling section, means to pass other air in countercurrent direction through said water in the water cooling section to cool said water, and means to return the recooled water to said cooling conduits.
13. In an air conditioning apparatus of the type described, a dehumidification section, means to pass air therethrough, means to contact the
- air with dehumidifying material therein, a cooling water conduit in the dehumidification section to remove heat from the air and dehumidifying materials, an evaporative jacket encircling said dehumidification section, means to pass said water after circulation through the dehumidification section through said evaporative jacket, and means to return water cooled in said evaporative jacket to the conduit in said dehumidification section. 10
14. In an air conditioning apparatus of the type described, a dehumidification section, means to pass air to be conditioned therethrough, means to contact the air in fine streams with flowing films of hygroscopic solution therein, a cooling water conduit in the dehumidification section to remove heat from the air and hygroscopic solution, means to separate said air and hygroscopic solution, means to recirculate the hygroscopic solution through the dehumidification section in contact with further air to be conditioned, an evaporative cooling jacket for said dehumidification section, and means to pass said water after circulation through the dehumidification section through said evaporative cooling jacket to cool said water for recirculation through the dehumidification section. 15
15. In an air conditioning apparatus of the type described, a dehumidification section, means to pass air therethrough, means to contact the air with dehumidifying materials therein, a cooling water conduit in the dehumidification section to remove heat from the air and dehumidifying materials, an evaporative cooler surrounding a portion of said dehumidification section, and means to pass said water after circulation through the dehumidification section through said evaporative cooler, means in said evaporative cooler to divide the water into fine portions, means to pass air in contact with said water to cool the water by evaporation, and means to recirculate said cooled water through the dehumidification section. 20
16. In an apparatus for dehumidifying and cooling air by the use of hygroscopic materials, a section to contain the hygroscopic materials, means to pass air through said hygroscopic materials, heat exchange units in said section in contact with said material and through which water may be circulated to remove heat from said hygroscopic materials, means to cool said water and further remove heat from said hygroscopic materials comprising an evaporative cooling chamber separated by a heat conducting wall from said section, means to maintain a supply of water in said cooling chamber, means associated with said evaporative cooling chamber to reduce the partial pressure of water therein, and means to circulate water through said evaporative cooling chamber and heat exchange units. 25
